US00D593897S

(12) **United States Design Patent**
Schneider

(10) **Patent No.:** **US D593,897 S**
(45) **Date of Patent:** **** Jun. 9, 2009**

(54) **GEMSTONE, OR ORNAMENTAL OBJECT
MADE OF GLASS**

(75) Inventor: **Florian Schneider**, Absam (AT)

(73) Assignee: **Swarovski Aktiengesellschaft**, Triesen (LI)

(**) Term: **14 Years**

(21) Appl. No.: **29/309,669**

(22) Filed: **Sep. 25, 2008**

(30) **Foreign Application Priority Data**

May 28, 2008 (EM) 000941620-0001

(51) **LOC (9) Cl.** **11-01**

(52) **U.S. Cl.** **D11/89**

(58) **Field of Classification Search** D11/1-2,
D11/26-29, 89-92; 63/26-28, 32

See application file for complete search history.
